(57) **CLAIM**

The ornamental design for a base cover for a plant cultivating system, as shown and described.

DESCRIPTION

FIG. 1 is a perspective view of a base cover for a plant cultivating system showing my new design;

FIG. 2 is a front elevation view thereof;

FIG. 3 is a rear side view thereof;

FIG. 4 is a right side view thereof;

FIG. 5 is a left side view thereof;

FIG. 6 is a top plan view thereof; and,

FIG. 7 is a cross-sectional view taken along line 7-7 in FIG. 6. The bottom view is not ornamental and forms no part of the claimed design.
